Rufus B. Fowler,

Inventor

Francis V. Davis.

UNITED STATES PATENT OFFICE.

FRANCIS V. DAVIS, OF WORCESTER, MASSACHUSETTS, ASSIGNOR OF ONE-THIRD TO JOHN F. CHADWICK, OF SAME PLACE.

LAMP-BURNER.

SPECIFICATION forming part of Letters Patent No. 577,840, dated March 2, 1897.

Application filed February 10, 1896. Serial No. 578,693. (No model.)

To all whom it may concern:

Be it known that I, FRANCIS V. DAVIS, a subject of the Queen of Great Britain, residing at Worcester, in the county of Worcester and State of Massachusetts, have invented a new and useful Improvement in Lamp-Burners, of which the following is a specification, accompanied by drawings forming a part of the same and representing a lamp-burner embodying my invention.

Figure 1 represents a side view of one of my improved lamp-burners with a lamp-chimney held upon the burner. Fig. 2 is a bottom view of the lamp-burner. Fig. 3 is a central vertical section on line 3 3, Fig. 2. Fig. 4 represents a portion of the lamp-burner, with a part shown in sectional view representing the method of attaching the device for holding the lamp-chimney; and Fig. 5 is a sectional view on line 5 5, Fig. 4.

Similar letters refer to similar parts in the different figures.

My present invention relates to that class of lamp-burners adapted to burn kerosene-oil or other products of petroleum and requiring a lamp-chimney; and it consists in the construction and arrangement of parts as hereinafter described, and set forth in the subjoined claim.

Referring to the drawings, A denotes the base of the burner, provided with a screw-threaded section A', adapted to be screwed into the screw-threaded collar upon the lamp. The base A is provided with arms A², projecting radially from the edge of the base and supporting upon their free ends a plate B, perforated throughout its central section B', with its edge forming a seat or gallery for the foot C' of the lamp-chimney C. Surmounting the plate B is a dome D, extending over the upper end of a wick-tube D' and provided with a slot D², the above-mentioned parts being constructed like the corresponding parts of lamp-burners now in common use.

The device for retaining the lamp-chimney which embodies my present invention comprises a pair of elastic or yielding fingers E E', four pairs of these yielding fingers being arranged concentrically around the lamp-burner. The yielding fingers E E' of each pair are held in contact at E² when the lamp-chimney is removed, and their ends are bent in order to separate the tips of the fingers to form a triangular space E³, in order to receive

the foot of the chimney. From the point of contact E² the fingers E E' diverge, the inner finger E' passing through an opening B³ to its point of attachment with the burner, and the outer finger E is curved at E⁴, so as to be carried around and beneath the edge of the plate B to its point of attachment with the lamp-burner. I prefer to form the yielding fingers E E' of a single piece of flat elastic wire having a straight section E⁵, adapted to rest upon the upper surface of one of the arms A² and be attached thereto by means of the lips F F, which are integral with the arm A² and are bent over and upon the straight section E⁵ of the yielding fingers, thereby attaching them firmly to the upper side of the arm A². The lamp-chimney is applied to the burner by placing the foot C' of the chimney in the triangular space E³ between the divergent tips of the yielding fingers and pressing the chimney downward upon the gallery B², thereby separating the yielding fingers E E' and allowing their tension to be applied to the outer and inner sides of a lamp-chimney and clamping the chimney between them.

Although I consider it preferable to form the elastic fingers E E' from a single piece of elastic wire, they may be made of separate pieces, which may be attached to the lamp-burner in any suitable manner other than that shown and described.

What I claim as my invention, and desire to secure by Letters Patent, is—

In a lamp-burner the combination of a base A provided with radially-projecting arms A³, a plate B, having a central section B', and a chimney-seat B³ in a lower plane than said central section and having openings B³ between said seat and said central section, a dome D attached to said plate at the edge of said central section, and yielding fingers E and E' arranged in pairs and adapted to press against the outer and inner sides of the chimney, each pair of fingers being integral and attached to one of the arms A², with the outer finger turned around the edge of said plate B and with the inner finger passing through one of the openings B³, substantially as described.

Dated the 4th day of February, 1896.

FRANCIS V. DAVIS.
